UNITED STATES PATENT OFFICE.

CHARLES H. COURT, OF JERSEY CITY, NEW JERSEY.

DESIGN FOR PENCIL-CASES.

Specification forming part of Design No. **11,160**, dated April 15, 1879; application filed February 13, 1879.
[Term of patent 7 years.]

To all whom it may concern:

Be it known that I, CHARLES H. COURT, of Jersey City, in the county of Hudson and State of New Jersey, have originated and designed a Pencil-Case, of which the following is a full, clear, and exact description, reference being had to the accompanying drawings, making part of this specification, in which—

Figure 1 is a side view of the new design for a pencil-case. Fig. 2 is a top view of the case.

This design relates to cases which are to contain pencils; and the nature of my design consists in making the case in the form of a pistol, provided with a protruding pencil-nib, and with a ring through its hammer, the whole forming a new and original design to be used as a charm.

In the annexed drawings, A designates one part of a cylindrical barrel; A', the other part of the same; and a is a line or joint between the ends of the two parts A A'. The rear cylindrical part, A', is slightly larger in diameter than the longest cylindrical part, A; consequently a slight shoulder is left at a, as shown.

B designates the stock or handle portion of the design, which is of the configuration shown. A portion, b, of this stock or handle extends beneath the rear cylindrical portion, A', of the barrel, and from the bottom of the extension b extends a curved trigger, c. Directly above this trigger c, and rising from the top of barrel-section A' is a hammer, d, which is represented as down on a nipple, e, forming an arch, f, through which passes a ring, g.

From the end of the barrel protrudes a pencil-nib, C.

What I claim as my invention is—

The design for the pencil-case described and shown, having the form of a pistol, and provided with the sections A A', of different diameters, stock B, trigger c, hammer d, nipple e, ring g, passing through the arch of the hammer, and a nib, C, as shown.

CHARLES H. COURT.
